UNITED STATES PATENT OFFICE.

EDWARD A. C. PETERSEN, OF CHICAGO, ILLINOIS.

BAKER'S OVEN.

SPECIFICATION forming part of Letters Patent No. 569,799, dated October 20, 1896.

Application filed July 25, 1896. Serial No. 600,471. (No model.)

To all whom it may concern:

Be it known that I, EDWARD A. C. PETERSEN, a citizen of the United States, residing at the city of Chicago, in the county of Cook, 5 State of Illinois, have invented a certain new and useful Improvement in Bakers' Ovens, of which the following is a full, clear, and exact description, reference being had to the accompanying drawings, forming part of this 10 specification.

My present invention relates to certain improvements in the class of ovens shown and described in my Patent No. 252,054, issued January 10, 1882, and is particularly adapted 15 to bakers' ovens wherein steam is used during the baking process, as set forth in my Patent No. 512,623, issued January 9, 1894. Practical experience has demonstrated that where steam is used in this class of ovens it 20 destroys and loosens the mortar around the ends of the pipes that conduct the heat and products of combustion through the upper part of the baking-chamber. After the steam has thus acted upon the mortar a portion of 25 it escapes from the baking-chamber around these pipes, and there is also danger of smoke and gases entering the baking-chamber.

The object of my present invention is to so seal these pipes at their ends as to avoid any 30 possibility of the steam producing leakages around the pipes.

My invention consists in features of novelty hereinafter fully described, and pointed out in the claims.

35 Figure I is a vertical longitudinal section of a baker's oven embodying my invention. Fig. II is an enlarged detail vertical section taken on line II II, Fig. I. Fig. III is a similar view taken on line III III, Fig. I. Fig. IV 40 is a detail horizontal section taken on line IV IV, Fig. II. Fig. V is a perspective view of one section or member of the sealing-boxes.

Referring to the drawings, 1 represents a 45 baker's oven, which, as represented, is made in accordance with the patent referred to, 2 designating the pipes located in the upper

part of the baking-chamber and through which the heat and products of combustion pass from the rear to the front of the oven. To effectually seal the ends of these pipes 50 and avoid the difficulty referred to, I employ a two-part box for each end of each pipe, each section of each box consisting of a plate 3, having ends 4. (See Fig. V.) The ends 4 are provided with semicircular recesses 5 55 to receive the pipe, and back of the plate 3 the ends 4 have extensions 6 between which the brickwork is built in, as shown in Fig. IV. Two of these sections being placed together, as shown, completely inclose the end 60 of the pipe, and after they are placed in position and the brickwork built in behind them I fill the box with cement mortar, as shown in Figs. III and IV, thus completely sealing the ends of the pipes. The ends 4 of the boxes 65 fit snugly against the pipes, preventing the steam from reaching the mortar, and thus permanently tight joints at the ends of the pipes are secured.

I claim as my invention—

1. In a baker's oven, the combination of the 70 pipes for conducting the heat and products of combustion, boxes formed to receive said pipes, and a mortar filling; said boxes being each composed of two members, and each 75 member consisting of a plate 3 having ends 4 provided with semicircular recesses 5, substantially as and for the purposes set forth.

2. In a baker's oven, the combination of the 80 pipes for conducting the heat and products of combustion, and means for sealing the ends of the pipes consisting of boxes adapted to receive a mortar, each box consisting of two sections, and each section consisting of a plate 85 3 having ends 4 provided with extensions 6 and semicircular recesses 5, substantially as set forth.

EDWARD A. C. PETERSEN.

In presence of—
GEO. H. KNIGHT,
E. S. KNIGHT.
